Patented Sept. 21, 1976

241,520

VEHICLE WHEEL LOCKING NUT

Yoshinobu Fujita and Yasuji Fukuyama, Los Angeles, Calif., assignors to Fujita Industrial Co., Ltd., Santa Monica, Calif.

Filed Sept. 16, 1974, Ser. No. 506,284

Term of patent 14 years

Int. Cl. D8—08

U.S. Cl. D8—273

FIG. 1.

FIG. 2.

FIG. 3.

FIG. 4.

FIG. 5.

FIG. 1 is a perspective view of a vehicle wheel locking nut showing our design.

FIG. 2 is a side elevational view.

FIG. 3 is a top plan view.

FIG. 4 is a bottom plan view.

FIG. 5 is a side elevational view showing an alternate form of our design, the top plan view of which is identical to FIG. 3.

We claim:

The ornamental design for a vehicle wheel locking nut, as shown and described.
